UNITED STATES PATENT OFFICE.

THOMAS E. JOHNSTON, OF AMITE, LOUISIANA, ASSIGNOR TO GULLETT GIN COMPANY,
A CORPORATION OF LOUISIANA.

COTTON CLEANER AND SEPARATOR.

985,037.

Specification of Letters Patent. Patented Feb. 21, 1911.

Application filed April 17, 1908. Serial No. 427,660.

To all whom it may concern:

Be it known that I, THOMAS E. JOHNSTON, a citizen of the United States, residing at Amite, in the parish of Tangipahoa and State of Louisiana, have invented certain new and useful Improvements in Cotton Cleaners and Separators; and I do hereby declare the following to be a full, clear, and exact description of the invention, such as will enable others skilled in the art to which it appertains to make and use the same.

This invention relates to cotton cleaners and separators, and it consists in the improved apparatus hereinafter described for cleaning the product by the "vacuum method," that is, under reduced air pressure, and continuing the operation under atmospheric pressure.

In the accompanying drawings: Figure 1 is a side elevation of a cleaner and separator embodying the features of the present invention. Fig. 2 is a longitudinal vertical section through the structure shown in Fig. 1. Fig. 3 is an enlarged sectional view showing a catch and releasing means embodying certain features of the invention.

Referring to the drawing by numerals, 1 indicates an opening through which the cotton is drawn preparatory to cleaning by means of suction that is applied to opening 2. The suction created or applied at opening 2 may be provided by a suction fan 3 or any other desired means for creating a continuous suction at opening 2, so as to draw in cotton at opening 1 and to cause the cotton to travel through chute 4. The chute or receiving member 4 may be made from any desired material, but preferably is made from sheet metal pieces as 5 and 6, and with wooden end pieces for holding the metal pieces in place. Connected to the end of chute 4 at 7 is a wire netting or mesh 8 that extends to the rear and is secured to a plate 9. The mesh or wire netting 8 is adapted to pass from one side of the chute 4 to the opposite side for forming together with the bottom of the chute a way through which the cotton is adapted to be drawn. The plate 9 is positioned directly to the rear of opening 1 so that as the cotton enters chute 4 it will strike against the plate which is preferably metal, and will then pass downward to a feeding member or fan 10. In passing downward from plate 9 the cotton passes a perforated metallic plate 11. Dur-

ing the passage of the cotton from opening 1 to fan 10 it is subject to the action of suction from fan 3, and while being subject to such suction the dirt and other foreign matter is drawn through wire mesh 8, and the perforated plate 11, but is not affected by the suction after it has been engaged by fan 10. A plurality of baffle plates 12 are provided above screen 8 for receiving the impact of the dirt from the cotton and guides the dirt toward opening 2, and then the dirt enters fan 3 or passes out any other desired place as may be desired. The dirt or other foreign matter drawn through perforated plate 11 will also pass downward and out opening 2.

Fan 10 is rotated by shaft 13 that may be driven by any desired power (not shown). Fan 10 is adapted to receive and force downward cotton from chute 4, and by this particular construction and arrangement will receive and force downward the cotton, but will not permit suction from opening 2 to act below the fan as the blades of the fan are provided with flexible members 14 that, together with the blades, form an air-tight joint. By this construction and arrangement the fan 10 may be rotated at any desired speed and yet will not permit the least amount of suction to act below the fan, but will readily receive and force the cotton to the various mechanism below the fan. It will be observed on Fig. 2 that chute 4 is enlarged centrally and slightly constricted at its lower end 15 as well as at opening 1. This will prevent any undue clogging or stopping of the chute, and will permit the cotton to be fed properly to fan 10, and from thence to rollers 16 and 17.

Fan 10 is partially surrounded by sheet metal plates 18 and 19 so as to prevent the suction from opening 2 from acting upon any cotton that is passed below the fan and reached rollers 16 and 17. When cotton is forced against either of the rollers 16 and 17, the rollers will engage the cotton and force the same in a continuous stream to a comparatively large roller or cylindrical member 21. Chain 20 is adapted to pass over gear wheels 22 and 23, and also over gear wheels 24 and 25 so that whenever shaft 13 is rotated gear wheel 24 will be rotated as said gear wheel is rigidly secured to shaft 13. An idler 26 is provided for holding chain 20 in proper place and under proper

tension. As shaft 13 revolves and eventually revolves rollers 16 and 17, the rollers will receive the cotton and force the cotton by means of projections 27 and 28 into engagement with the spurs 29 of roller or cylinder 21. The spurs or projections 27 and 28 are preferably mounted upon their respective cylinders or rollers in a staggered or zigzag formation. The rollers 16 and 17 are adapted to rotate faster than fan 10, but do not at each rotation feed or draw the same amount of cotton so that if the cotton is being fed too fast into chute 4 fan 14 will become filled and will simply rotate full of cotton, but will not stop or be clogged up, but will permit rollers 16 and 17 to remove from between the blades of the fan the cotton as the rollers 16 and 17 dispose of the cotton already engaged thereby. By this action of rollers 16 and 17 a continuous strip of cotton is forced against roller 21 and is engaged thereby during the rotation thereof. As roller or cylinder 21 rotates it will force the cotton against a screen or wire mesh 30 and finally force the cleaned cotton out an opening 31 from which the cotton is adapted to be conveyed to a regular cotton gin to be ginned in the usual manner.

During the action of rollers 16, 17 and 21, the dirt and other foreign substances are removed by suction, through screen 30, and drop into chute 32, from which they are conveyed by an auxiliary chute 33 to a place of disposal. Chute 32 comprises end pieces struck on an arc corresponding with the curvature of screen 30 secured thereto so that when chute 32 is swung upon its hinges 34 from between the end sections of the housing 35 to expose roller 21 and the other mechanism in housing 35, screen 30 will also be lowered for inspection or cleaning as may be desired. In order to properly hold chute 32 in position a catch 36 is provided that engages a lug 37 upon the lower part of housing 35. An arm 38 is provided for engaging catch 36 and is adapted to be rotated by a shaft 39 which extends to the exterior or casing 35 and is provided with a handle or crack 40 so that whenever it is desired to swing chute 32 upon its pivot crank or handle 40 is swung for disengaging catch 36 and lug 37. Previous to the disengagement of catch 36 and lug 37 auxiliary chute 33 must be moved out of contact with chute 32 so as to permit a free swinging action of the chute.

In operation when it is desired to clean some cotton previous to feeding the cotton to a gin, the cotton is fed to opening 1 by any desired means and is drawn into chute 4 by suction from fan 3. As the cotton passes through chute 4 the same strikes against screen 8, and has part of the dirt and foreign matter removed therefrom by the suction from fan 3. The cotton con-

tinues to travel downward from chute 4 to the restricted portion 14 and as it passes perforated plate 11 additional dirt that has become loosened during the travel of the cotton may pass therethrough and out opening 70 2. A window 41 if desired may be provided for viewing the cotton as the same travels through the chute. Cotton passes from chute 4 into fan 10 and is forced therefrom to rollers 16 and 17 and is formed into a continuous strip by these rollers, and at the same time additional dirt and foreign matter are removed by the reforming of the cotton. The cotton then passes to roller 21 and is again agitated during its travel 80 around screen 30, and finally passes out opening 31. During the tearing or reforming action of rollers 16 and 17 and also roller 21 the dirt and foreign matter are removed and are permitted to drop through screen 30 into 85 chute 32 and from thence to auxiliary chute 33. By this construction most of the dirt is removed by the suction from fan 3 as the cotton passes through chute 4, but any dirt or foreign matter that is mixed in the cotton 90 so thoroughly as not to be removed by the suction is removed by the action of rollers 16 and 17, together with roller 21 and screen 30 so that when the cotton is finally taken from the machine at 31 it appears in 95 a substantially continuous strip though in a slightly fluffy condition but cleaned of substantially all dirt and other foreign matter, and is ready for the gin.

The plate 19 is secured to a removable portion 42 of housing 35 and may be moved away from fan 10 as clearly shown in dotted lines in Fig. 2. This will permit an examination of the fan for cleaning or otherwise as may be desired.

What I claim is:

1. In a device of the class described, a chute, a substantially cylindrical valve casing communicating with the chute at one side and open at the opposite side, a rotary valve within the casing, means for exhausting air from the chute above the valve casing, spaced retarding rollers journaled adjacent the opening, a spiked roller disposed below and between the retarding rollers a screen adjacent to the spiked roller, a swinging chute section beneath said roller and extending radially therefrom, such screen arranged transversely of the swinging section and being carried thereby, a catch carried by the swinging section, and a rod adjacent to said section and provided with a projecting portion arranged to release the catch.

2. In a pneumatic cotton cleaning apparatus, a chute, a partition wall therein extending lengthwise of the chute, an imperforate valve casing, said partition wall constituting one side of the valve casing and being provided with apertures above such

casing, means for exhausting air from above such casing, a rotating air valve journalized in the casing, rollers disposed adjacent the casing, a spiked roller adjacent the rollers last mentioned, a screen adjacent the spiked roller, a swinging chute section beneath the spiked roller and extending radially therefrom, said screen arranged transversely of the swinging section and being carried thereby, a catch carried by the swinging section,

and a rod adjacent said section and provided with a projecting portion arranged to release the catch.

In testimony whereof I affix my signature in presence of two witnesses.

THOMAS E. JOHNSTON.
